US00D941236S

(12) **United States Design Patent** (10) Patent No.: **US D941,236 S**
(45) Date of Patent: **** Jan. 18, 2022**

(54) **CANOPY WITH SOLAR POWERED ELECTRONIC MENU BOARD**

(71) Applicant: **Manufacturing Resources International, Inc.**, Alpharetta, GA (US)

(72) Inventors: **William Dunn**, Alpharetta, GA (US); **Gerald Fraschilla**, Snellville, GA (US)

(73) Assignee: **Manufacturing Resources International, Inc.**, Alpharetta, GA (US)

(**) Term: **15 Years**

(21) Appl. No.: **29/804,585**

(22) Filed: **Aug. 20, 2021**

Related U.S. Application Data

(62) Division of application No. 29/711,255, filed on Oct. 29, 2019, now Pat. No. Des. 934,159.

CLAIM

The ornamental design for a canopy with solar powered electronic menu board, as shown and described.

DESCRIPTION

FIG. 1 is a front perspective view of a canopy with solar powered electronic menu board;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.

The broken lines shown represent environmental subject matter and form no part of the claimed design.
